(57) **CLAIM**

The ornamental design for a portable computing device stand, as shown and described.

DESCRIPTION

FIG. 1 is a perspective view of a portable computing device stand showing our new design in a closed configuration;

FIG. 2 is a second perspective view thereof;

FIG. 3 is a third perspective view thereof;

FIG. 4 is a top perspective view of a portable computing device stand showing our new design in an opened configuration;

FIG. 5 is a second top perspective view thereof with a compartment cover removed;

FIG. 6 is a third top perspective view thereof;

FIG. 7 is a bottom perspective view thereof;

FIG. 8 is a top plan view thereof;

FIG. 9 is a bottom plan view thereof;

FIG. 10 is a rear elevation view thereof;

FIG. 11 is a front elevation view thereof;

FIG. 12 is a left-side elevation view thereof; and

FIG. 13 is a right-side elevation view thereof.

FIG. 14 is a top perspective view of a portable computing device stand showing our new design in a state of use;

FIG. 15 is a second top perspective view thereof;

FIG. 16 is a third top perspective view thereof;

FIG. 17 is a fourth top perspective view thereof

FIG. 18 is a top plan view thereof;

FIG. 19 is a bottom plan view thereof;

FIG. 20 is a front elevation view thereof;

FIG. 21 is a rear elevation view thereof;

FIG. 22 is a left-side elevation view thereof;

FIG. 23 is a right-side elevation view thereof;

FIG. 24 is a right-side elevation cross-sectional view taken from line 24-24 of FIG. 18; and,

FIG. 25 is another right-side cross-sectional view thereof.

(Continued)

The broken lines shown in the drawings represent portions of the portable computing device stand that form no part of the claimed design.
